UNITED STATES PATENT OFFICE.

CONRAD FREDRICH BARTLING, OF GREENVILLE, OHIO.

FENCE-MACHINE.

SPECIFICATION forming part of Letters Patent No. 350,967, dated October 19, 1886.

Application filed December 18, 1885. Serial No. 186,070. (No model.)

To all whom it may concern:

Be it known that I, CONRAD FREDRICH BARTLING, a citizen of the United States of America, residing at Greenville, in the county 5 of Darke and State of Ohio, have invented certain new and useful Improvements in Fence-Machines, of which the following is a specification, reference being had therein to the accompanying drawings.

10 My invention relates to certain novel improvements in machines for making wire-and-picket fences, which improvements will be fully understood from the following description when taken in connection with the annexed drawings, in which—

Figure 1 is a perspective view of my improved machine complete, having the picket-wires applied, but not the pickets. Fig. 2 is a view in detail of wire-holders connected to 20 the stretcher-post. Fig. 3 is a horizontal section through the stretcher-post. Fig. 4 is a horizontal section through line *x x* on Fig. 1, showing a top view of one of the spacers and its clamping-holders. Fig. 5 is a vertical sectional detail taken in the plane indicated by 25 dotted line *y y* on Fig. 2.

Referring to the annexed drawings by letters, A designates a vertical post, to which the 30 twisters A' A' A² are applied. This post has a shoe, K, secured to its lower end, upon the extension of which the slats are supported while being secured to the fence-wires L. This shoe has a wheel, I, applied to one side of it, which sustains the post A during the operation of 35 the machine. On the ends of the tubular twisters sprocket-wheels B B' B are keyed, to which an endless chain is applied, as indicated in dotted lines, Fig. 1, and to the highest tubular twister A' a hand-crank, C, is applied 40 by turning which the three twisters will receive rotation for putting twists in the wires between the pickets.

D D designate adjustable spacers, the flaring bifurcated ends of which are designed to 45 receive a slat when sustained upon the extension of the shoe K during the act of confining the slat in the wires L. The straight portions d of the spacers are transversely grooved on their upper edges at d', and each spacer is 50 clamped between two of the bearing-plates e e' of a twister by means of a clamping-bolt, E, which crosses one of said grooves d' and passes

through the said bearing-plates and through the post A. By loosening the plates e e' the two spacers can be adjusted endwise for varying the spaces between the slats of different fences. If desired, vertical notches e' may be made in the sides of the spacers for receiving teeth e² on the plates e e', (shown in Fig. 4,) thus aiding in rigidly holding the spacers 55 against slipping after being properly adjusted.

F designates a shifting bar, which is sustained upright and parallel to the post A. This bar F is provided with angular plates H H at its ends, and also with arms F' F', rigidly 60 secured to it, which arms are pivotally attached to the arms G' G' of an oscillating shaft, G, that has its bearings in eyes, f f, on the adjustable spacers D D, as shown in Fig. 1. When the said angular plates H H are thrust in between 65 the pickets already secured in place, the lever or arm G' is used to forcibly draw the machine toward the completed fence to force the picket last inserted to its place, also to force the machine back away from the picket after 70 the wires are twisted to permit the insertion of another picket.

U designates a pedestal, from which rises vertically a bar, W, rigidly secured therein, and terminating at its upper end in a screw, 75 W'. On this bar W, which is square in cross-section, two hollow bars, X X', are applied, on the lower ends of which are knife-edge bearings or offsets S. On the upper ends of the hollow bars X X' are curved horns O O, for 80 the purpose of holding the coils of wire from 85 which the fence-wires are drawn.

N N designate guides for the fence-wires, which guides are loosely applied on the bar W, and constructed with bifurcations g g, between 90 which the fence-wires are guided on their way to the twisters, as shown in Figs. 1 and 2. The knife-edges S S bear upon said guides and cause them to press the wires upon the surfaces o o at the inner termini of the coil-supporting 95 horns O O with more or less force, regulated by a nut, V, on the screw-threaded end of the bar W, according to the degree of tension required. The guide at the upper end of the section X' is pressed down by a plate, S', having 100 knife-edge bearings, which plate is acted on directly by the nut V. It will thus be seen that the pressure of the three guides N upon the three pairs of wires is controlled by adjust-

ing the nut V, and that such pressure will be practically equal on all of the wires L. The lowest wire-guide N presses its wires upon the elevated surface o of the pedestal U.

- 5 P designates a vertical windlass, which is connected by wires or chains T to some fixed object. This windlass passes through eyes P' on the guides N, and is sustained upon the base of the pedestal U, as shown in Fig. 1.
- 10 The upper end of the windlass P has an eye, P', through which passes a hand-lever, Q, adapted to engage with the rack-teeth R, surrounding the eye P' of the highest wire-guide N.
- 15 The operation is as follows: Dig all of the post-holes, but plant only the first post to the left and properly brace it to sustain the strain on the wires. Set up the twister to this post. Turn the crank C so that the wire-holes are on a level. Put the wires L through the twisters 20 and fasten them securely to said post. Then place the stretcher in the first post-holes, mounted on its pedestal. Now put the wires L from each twister into the notches of the guides N. The shaft with the nut on top must be toward 25 the twister. There should be no twist in any pair of wires from twister to stretcher. Fasten the wires or chains T to some solid post or tree on line of fence and tighten by means of windlass. Now draw each wire L through the guides 30 as far as can be done by hand, and tighten the same by screwing down the nut V, after which the wires are drawn as tight as is required by means of the windlass and held by dropping the hand-lever Q between two teeth of the rack-teeth R. After stretching the wires, put a thin board under the twister on the line of the fence, for the twister to stand on. Push the twister close to the post, give crank C two turns, push the twister back, put the first slat between the 35 pairs of wires and rest it upon the foot K, and press it up close to the twist. Now turn the crank C opposite from the first turn two turns. After the first two slats are secured to the wires, 40 put the bar F in the first slats and use the handle G to draw up the slats and to push the twister back. The turn of the crank C must be reversed every two slats to keep the twist out of the wire between the twister and the stretcher.

After passing a post-hole, plant a post and fasten all the wires to it.

Having described my invention, I claim—

1. In a portable fencing-machine, the combination, with the post A, provided with a foot at its lower end for a slat to rest upon, and also with rotary twisters, of the adjustable bifurcated slat-spacers, and the shifting bar F, provided with angular plates H and connected by arms to vibrating lever-arms sustained by said spacers, substantially as described.

2. The adjustable spacers D, notched as described, and confined by means of the bearing-plates of the twisters and a bolt passed through these plates and through the post A, substantially as described.

3. The combination of the bar W, sustained by a pedestal and provided with a nut on its upper end, the hollow sections X X', provided with horns, bearing-surfaces, and knife-edges, the notched guides N, and the plate S', for the purpose of clamping the fence-wires, substantially as described.

4. The combination, with the post W and its wire-clamping sections, as described, of the windlass P, guided by eyes on the guides N, provided with a lever at its upper end, and also with an arresting-rack for this lever, substantially as and for the purposes described.

5. A portable fencing-machine consisting of the following elements in combination: the post A, provided with rotative twisters, a rolling support, and a slat-supporting shoe, the adjustable spacers, the shifting bar F, connected by arms to vibrating arms sustained by said spacers, the vertically-supported shaft provided with clamping devices for the fence-wires, as described, and the windlass P, its loosely-attached hand-lever, and the engaging teeth therefor, all constructed and adapted to operate substantially in the manner specified.

In testimony whereof I affix my signature in presence of two witnesses.

CONRAD FREDRICH BARTLING.
